UNITED STATES PATENT OFFICE.

JOHN J. KAISER, OF DAYTON, OHIO.

FIRE APPARATUS.

1,410,190.

Specification of Letters Patent. Patented Mar. 21, 1922.

Application filed April 17, 1920. Serial No. 374,658.

To all whom it may concern:

Be it known that I, JOHN J. KAISER, a citizen of the United States, residing at Dayton, in the county of Montgomery and State 5 of Ohio, have invented certain new and useful Improvements in Fire Apparatus, of which the following is a specification, reference being had therein to the accompanying drawing.

10 This invention relates to improved fire apparatus, having particular reference to truck ladders and ladder-hoisting and controlling means whereby ladders of this character may be more effectually handled.

15 The apparatus as a whole may be mounted on any suitable truck, or other supporting means and may be operated direct as mounted on the truck through suitable operating connections with the motor of the truck, or

20 may be demounted from the truck and operated through suitable connections with any available source of power.

The main object of the invention is to provide means whereby extensible scaling 25 ladders, of the general character of fire truck ladders, may be power-operated, as distinguished from the present common practice of manual operation; the result to be effected by power operation consisting in 30 quicker and more positive manipulation of the ladders and, therefore, a greater degree of safety in the work that is to be performed in connection with their use.

As shown in the drawings and herein 35 described the invention contemplates the use of air compressors and pneumatic controls for raising and lowering extensible ladders of any suitable construction and for maneuvering the same relative to buildings which 40 are to be scaled by the use thereof.

In the operation of trucks equipped with the apparatus, in the preferred form of construction illustrated in the accompanying drawings, it is contemplated to use an air 45 pressure storage tank of ample capacity to perform all initial operations of the ladders, such as maneuvering the same relative to a building, and extending the ladders to scale the building, and to maintain the storage tank normally charged at the required 50 pressure to perform these operations. Thus the apparatus will be at all times normally ready for instant use irrespective of the condition of the motor or other source of power 55 for charging the storage tank.

It is a further object of the invention as herein contemplated to employ in connection with the storage tank an air compressor directly connected to the truck motor, when a motor-operated truck is used, or otherwise with an independent motor, whereby the pressure of the storage tank may be maintained at normal whether the apparatus is at rest or in operation.

In the construction shown, it is further 60 contemplated to employ a direct-operating air pressure chamber in connection with the ladder hoisting means whereby the action of the air on the hoisting means will be equalized and the action and control of the 65 ladders will be direct and positive with the possibility of failure in operation minimized to a negligible degree.

As far as I am aware I am the first to 70 evolve a practicable apparatus having the general characteristics of the present construction and the broad underlying principles of invention defined in the appended claims. It will be understood that the invention relates to these broad principles rather than 75 to the minor details of construction which may be modified in various ways without departing from the basic features or the spirit of the invention.

While the invention is herein illustrated 80 and described as applied to pneumatic apparatus, it will be understood that pressure mediums other than air, such as water or other suitable liquids, may be employed to effect the automatic maneuvering of the ladders, the pneumatic apparatus being herein 85 shown for the purposes of illustration only.

In the drawings:

Fig. 1 is a plan view of a truck and apparatus embodying the present invention in 90 one form;

Fig. 2 is a side elevation of the truck frame and apparatus shown in Fig. 1; a ladder and part of the machinery connected therewith being shown in dotted lines and part 100 of the turn-table being shown in section.

As shown in the drawings, the ladder-operating apparatus may be mounted on any suitable truck, preferably on a motor-operated truck, suitable connections being employed to operate the ladders with power supplied from the truck engine.

Thus as illustrated in Fig. 1 of the drawings there is a truck frame 1 supported on ground wheels 2. Mounted on the frame at 110

the front of the truck in the usual manner is an engine 3 which may be of any suitable type and capacity to meet the operating requirements of the truck and the pneumatic 5 ladder apparatus thereon.

A storage battery 4 and electrical motors 5, 6 and 7 are employed as here shown in connection with the engine 3, a switch or controlling device 8 being connected with 10 the different battery circuits to control operation of the respective devices. Thus the engine 3 may be operated independently of the motors 5, 6 and 7 or jointly with any one of the motors, as may be desired and 15 as may be determined by manipulation of a switch 8 which is here shown in more or less conventional form, it being understood that the switch and wire connections may be of the usual forms of well known construction.

The motor 5, as here shown, is gear-connected to an air compressor 9, any suitable gearing, as indicated at 10 and 10^a being employed to effect the connection between 25 the motor and compressor.

The motor 6 is geared to a turn-table 11, mounted in any suitable manner on the frame 1 of the truck through gear connections 12 and 12^a and a worm-gear drive 13.

30 The motor 7 is mounted on the turn-table 11 and is geared to the ladder elevating mechanism which will presently be described by gear connections 18, 19, 20 and 21, the gear 18 being a small gear secured to the 35 motor shaft, the gears 19 and 20 intermediate gears, and the gear 21 a large gear secured to one end of a direct-action air compressor chamber 22 mounted in suitable bearing supports 23 on the turn-table 11.

40 A clutch 24, as here shown, is interposed between the motor 7 and chamber 22, whereby the gear connections therebetween may be thrown into and out of operative relation.

Supported on the frame 1 in the rear of 45 the turn-table 11, as here shown, are storage or reserve air pressure tanks 14 which are connected to the air compressor 9 by pipe couplings 15, whereby the tanks may be charged with air from the compressor, a 50 check valve 16 and a cut-off valve 17 being employed respectively to regulate the pressure at which the tanks 14 may be charged and to cut out the connection between the air-compressor and tank at times when the 55 tanks are full-charged and the apparatus is inoperative.

The compression tanks 14 are connected to the direct-action chamber 22 by a suitable coupling, consisting as here shown of a 60 section of pipe 25 having a check valve 26 and cut-out valve 27 arranged therein, whereby to regulate the charging of the chamber 22 with air from the tanks 14. To accommodate the movement of the turn-table upon which the chamber 22 is mounted

the connection to the tank from the pipe 25 is made by means of a section of flexible hose 28.

The air chamber 22, as stated, is mounted on the turn-table 11 and is also mounted in 70 the bearing supports 23 to rotate therein. Supported on the chamber is an extensible ladder, here shown as consisting of two sections 29 and 30. It will be understood, however, that any desired number of ladder 75 sections may be employed, the present construction being for the purposes of illustration only. Section 29 of the ladder rests at its base on the chamber 22 and may be secured thereto in any suitable manner. Section 30 of the ladder is mounted to be 80 extended longitudinally of section 29, the connections between the sections being of the usual nested construction in extension ladders. While the ladders are here shown in sections it will be obvious that with suitable modifications rope or other collapsible ladders may be employed.

Also mounted on the chamber 22 are two opposite tubes or pipes 31, having extensible 90 tubes 32 telescopically mounted therein, the joints 33 between the tubes 31 and 32 being packed in any suitable manner to prevent any material escape of air therethrough.

The tubes or pipes 31 are mounted in any 95 conventional way, as by their connection with the couplings 31^a as to permit of the slight lateral movement between them to accommodate the distance between the pipes 32 as they telescope in and out of the pipes 100 31. At their outer free ends the tubes 32 are joined together with a telescopic cross-head 34 which is connected to the section 30 of the ladder by ropes or cables 35, and has secured thereto outwardly projecting guide 105 and supporting wheels 36 adapted to contact with a wall of a building when the ladders are positioned relative thereto. This telescopic cross head permits the approach and receding of the ends of the pipes 32 in 110 their movement into and out of pipes 31.

The tubes 31 are directly connected to the air chamber 22 in any suitable manner, as by ports 37, and tubes 32 are preferably closed at their inner ends to form a head 115 for the action of the air thereon. Air is introduced to the chamber 22 and therefore direct to tubes 31 by means of valve 27 which will act to force tubes 32 and ladder section 30 secured thereto outwardly to any 120 desired extent within their capacity for extension. When the ladders have been extended they may be maintained in such relation by closing the cut-off valve 27.

To insure against any possibility of failure or accident in the pneumatic apparatus when the ladders are in extended relation and firemen or others ascending or descending thereon, any suitable mechanical means may be employed to positively lock the ex- 130

- tended tubes and ladder in any extended position. Such means are illustrated in the drawings in devices applied to the opposite tubes 31 and 32 consisting of a toothed bar 38 pivotally secured to the cross head 34 and adapted to pass between the arms of the bifurcated member 39 secured to the ends of tubes 31. The bar 38, as here shown, is provided with notches 40 adapted to be engaged by a locking pawl 41 pivoted on the member 39. The locking pawl is shown as having one end weighted and is adapted to be released from the bar 38 by means of the pull string 42, the pawl being spring-controlled to return same to locking engagement with the teeth 40 whenever the pull string 42 has been released.
- As best shown in Fig. 2 of the drawings an auxiliary air compressor apparatus may be employed to perform or assist in performing the initial step of raising the ladders. As here shown an air cylinder 43 is mounted on the rear of the truck and is connected to the air tank 14 by suitable connections 44 with the valve 27, whereby with the opening of the valve to charge the chamber 22, the initial movement to open the valve may be utilized to charge the cylinder 43. The cylinder may have any suitable piston operable therein having a lifting head 45 secured thereto externally of the cylinder, and adapted to loosely support thereon the opposite tubes 31. Thus by charging the cylinder 43 with air in the manner described the tubes 31 and 32 together with the extensible ladders secured thereto may be raised to the extent indicated in Fig. 2 of the drawings as shown in dotted lines.
- From the foregoing detailed description and from the accompanying drawings the construction and operation of the improved apparatus will be readily understood.
- As here shown it is contemplated that all the required power for operating the apparatus will be supplied from the truck motor. Thus the storage battery 4 may be charged from the motor through any suitable connection, such as a generating motor, and the motor 5 may be supplied with current from the battery or direct from the generator to operate the air compressor 9. The reserve air pressure tank 14 may be charged with air as required either to maintain the reserve air pressure therein or to maintain operating pressure when the apparatus is at work.
- The motor 6 may be supplied with current in like manner to operate the turn-table to position the ladders relative to a building or otherwise where the same are to be raised.
- The motor 7 will likewise be supplied with current to rotate the chamber 22 and the ladder extending apparatus secured thereto to raise the pneumatic tubes 31 and 32 and the ladders therewith to the desired angle for extending the ladders, the auxiliary air pressure device 43 also being employed in this connection. Finally, the ladders will be extended by charging the air chamber 22 from the tank 14, as herein described. The action of the air in the chamber 22 will be to equalize the pressure on the closed ends of the tubes 32 so that the projections of the tubes and the ladder section 30 will be in balanced relation.
- While the construction herein shown is essentially of a preferred form, it will be understood that the invention deals with the apparatus as a whole rather than with the detail arrangements. Various modifications may be made in the apparatus, both as to details of construction and arrangement of the different units of the apparatus in their coordinated relations without departing from the underlying principles and the spirit of the invention as defined in the appended claims.
- Having thus fully described my invention, what I claim as new and desire to secure by Letters Patent, is:—
1. In an apparatus of the character described, the combination with a motor truck, an air compressor operatively connected with the motor thereof and a reserve air pressure tank connected to the air compressor, of a direct air pressure chamber connected to the reserve air tank and rotatively adjustable relative thereto, telescopic air tubes mounted on said air chamber and adapted to be charged with air therefrom, and an extensible ladder connected to said tubes whereby said tubes and ladder may be angularly adjusted and compressed air may be employed in said apparatus to expand said tubes longitudinally to extend said ladders.
  2. In an apparatus of the character described, the combination, with a motor and an air compressor operatively connected therewith, of a reserve air pressure tank connected to the air compressor, a direct-action air pressure chamber connected to the reserve air tank and mounted to rotate in horizontal and vertical planes relative thereto, air-operated extensible members mounted on said air chamber and adapted to be charged with air therefrom and an extensible ladder connected to said members whereby compressed air may be employed in said apparatus to expand said members longitudinally to extend said ladders.
  3. In an apparatus of the character described, the combination, with a motor and an air compressor operatively connected therewith, of an air pressure chamber connected to the air compressor and adapted to be adjusted rotatively relative thereto, air-operated extensible members mounted on said air chamber and adapted to be charged with air therefrom, and an extensible ladder

- connected to said members whereby compressed air may be employed in said apparatus to expand said members longitudinally to extend said ladders.
- 5 4. In an apparatus of the character described, the combination with a frame, a motor, and an air compressor operatively connected to said motor, of air-operated extensible members mounted for movement 10 relative to said frame, and an air pressure chamber communicating with the air compressor and rotatively mounted on said frame, said extensible members being connected with said chamber for rotative movement therewith in regard to said frame, said extensible members to be charged from said air-pressure chamber, an extensible ladder connected to said members whereby compressed air may be employed in said apparatus 15 to expand said members longitudinally to extend said ladders, and locking devices cooperating with said members to maintain the ladders in said extended relation.
- 20 5. In an apparatus of the character described, the combination with a frame, a motor, and an air compressor operatively connected to said motor, of air-operated extensible members mounted for movement 25 relative to said frame, and an air pressure chamber communicating with the air compressor and rotatively mounted on said

frame, said extensible members being connected with said chamber for rotative movement horizontally and vertically therewith 35 in regard to said frame, said extensible members to be charged from said air-pressure chamber, an extensible ladder connected to said members whereby compressed air may be employed in said apparatus to expand said members longitudinally to extend 40 said ladders, and an auxiliary air-operated mechanism cooperating with said means and the air pressure chamber to partially effect 45 said vertical adjustment.

5 6. In an apparatus of the character described, the combination with a frame, a motor, and an air compressor operatively connected to said motor, of a turntable on said frame, and vertically-adjustable air-operated extensible members thereon, and an air pressure chamber communicating with the air compressor and rotatively mounted on said turntable, means to operate the turntable, and separate means to 55 effect the vertical adjustment of said extensible members, and an extensible ladder connected to said apparatus whereby compressed air may be employed in said apparatus to expand said members longitudinally 60 to extend said ladders.

In testimony whereof I affix my signature.

JOHN J. KAISER.
